UNITED STATES PATENT OFFICE.

MERRILL A. FROST, OF SUMPTER, MICHIGAN.

IMPROVEMENT IN HARNESS.

Specification forming part of Letters Patent No. 222,485, dated December 9, 1879; application filed September 2, 1879.

To all whom it may concern:

Be it known that I, MERRILL A. FROST, of Sumpter, Wayne county, Michigan, have invented an Improvement in Plow-Harness, of which the following is a specification.

The object I have in view is to produce harness for supporting a double-tree and whiffletrees below and between the legs of a span of horses, with a single connection with the plow-clevis, so that such whiffletrees or the double-tree cannot work forward in use and strike the fore legs of the horses, as is the case with harnesses now in use for such purpose.

The invention consists in the peculiar construction of the harness, in combination with the double-tree and whiffletrees.

In the accompanying drawings, Figures 1 and 2 are views in perspective, showing the harness placed on a pair of horses; and Fig. 3, a perspective view of the double-tree and its whiffletrees.

The double-tree G is connected, by a central chain extending between the horses, as shown, with the plow-clevis.

On the ends of the double-tree are pivoted the curved whiffletrees F, having ends bent back into hooks f.

The double-tree is supported transversely beneath the bodies of a pair of horses, and between the fore and hind legs of the same, by hooking the whiffletrees into rings C, hanging down on the sides of the horses a little in the rear of the center of their bodies. These rings C are connected by short tugs B with the collar and harness A, and by hip-straps D with the back-strap E, which extends from the collar and hames to the crupper E'. By these means the rings C are supported in one position and prevented from slipping forward, which would allow the double-tree to swing against the fore legs of the horses.

What I claim as my invention is—

In a plow-harness, substantially as described, the whiffletree-rings C, hung from the hames by tugs B, and from the back-strap and crupper E E' by the hip-straps D, whereby the double-tree is prevented from swinging forward against the fore legs of the horses.

MERRILL A. FROST.
